Inventor
Charles Doyle
By Arthur H. Steele, *Atty*

UNITED STATES PATENT OFFICE.

CHARLES DOYLE, OF SAN FRANCISCO, CALIFORNIA.

DENTIFRICE-DISPENSING DEVICE.

1,375,954.

Specification of Letters Patent. Patented Apr. 26, 1921.

Application filed January 28, 1921. Serial No. 440,792.

To all whom it may concern:

Be it known that I, CHARLES DOYLE, a citizen of the United States, residing in the city and county of San Francisco and State 5 of California, have invented a new and useful Improvement in Dentifrice-Dispensing Devices, of which the following is a specification.

My invention relates to improvements in 10 a device for dispensing tooth paste and the like wherein dispensing means operate in in conjunction with brush engaging means to dispense paste onto a brush when the brush is withdrawn for use.

15 The primary object of my invention is to provide improved means for facilitating the dispensing of tooth paste and the like onto a brush.

Another object is to provide an improved 20 tooth brush retainer arranged to dispense tooth paste to a brush when withdrawn therefrom.

A further object is to provide improved 25 means for controlling the dispensing of tooth paste from a dispensing container of the character described.

I accomplish these and other objects by 30 means of the device disclosed in the drawings forming a part of the present specification 35 wherein like characters of reference are used to designate similar parts throughout said specification and drawings and in which:—

Figure 1 is a vertical section of my in- 40 vention.

Fig. 2 is a broken front elevation of the 45 device disclosed in Fig. 1.

Fig. 3 is a horizontal section taken along 50 the line 3—3 of Fig. 2 in the direction in- 55 dicated.

Fig. 4 is an enlarged broken detail of the 60 plunger operating means, the section being taken along the line 4—4 of Fig. 1, in the direction indicated.

5 Fig. 5 is an enlarged broken section taken at the line 5—5 of Fig. 1 in the direction indicated.

Referring to the drawings the numeral 1 0 is used to designate in general a housing open at the bottom and closed at the top thereof, and provided with a suitable bracket 2 whereby the housing 1 may be secured upon a wall. A receptacle 3 provided with an outlet vent 6 is removably secured 5 in the housing 1 by any suitable means such

as the thumb screw 7 disclosed in the drawings. The bottom of the receptacle 3 is closed by a cap 5 threaded thereonto.

Slidably mounted within the receptacle 3 I have provided a plunger 8 provided with 60 a stem 9 extending outwardly through the bottom of the receptacle, through an aperture 11 provided in the cap 5. Ratchet teeth 12 are formed upon the stem 9 for a purpose hereinafter explained.

65 A tube 14 provided with a longitudinal slot 16 is threaded onto an extension 17 provided on the cap 5 to surround the outwardly extending portion of the stem 9 as disclosed in Fig. 1 of the drawings. The 70 outer surface of the tube 14 is threaded to receive a nut 18 arranged to regulate the movement of the plunger 8 as hereafter described.

75 A brush engaging member 21 provided with spring clips 22 inwardly turned to grip the body portion of a tooth brush 24, is provided with a bearing portion 26 arranged to be slidably mounted upon the upper portion of the tube 14. A pawl 80 27 is operatively mounted upon the member 21 adjacent the bearing portion 26 in such a manner that the ratchet engaging portion of the pawl 27 will extend through the slot 16 in tube 14 to engage the ratchet teeth 85 of the stem 9. A spring 28 is provided to retain the pawl 27 in engagement with the teeth 12.

80 A slide 29 is mounted upon the member 21 to normally close the outlet vent 6. 90 The brush engaging member 21 is normally retained in the position disclosed in Fig. 1 of the drawings with the bearing portion of the member 21 at its uppermost limit of movement as defined by the cap 5, by a 95 spring 31 supported around the tube 14 by the nut 18. The nut may be advanced or receded along the tube 14 to define a lower limit of movement suited to the requirements of the user.

100 The clips 22 of the member 21 are spaced from the receptacle 3 sufficiently to permit the insertion of the brush thereinto in such a manner that the ends of the bristles 32 will be in vertical alignment with the outlet vent 6. A window 33 is provided in the front portion of the housing 1 to permit observation of the member 21 to facilitate the introduction of the brush thereinto.

110 In operation my invention is as follows.

The receptacle 3 removed from the housing which is arranged to be secured upon a wall in the position shown, by unscrewing the thumb screw 7 to release the receptacle. 5 The cap 5 is now removed from the receptacle. The pawl is manually moved to release the stem 9 and the plunger 8 positioned at its innermost position within the receptacle 3. Tooth paste 34 of any desired character may now be placed in the receptacle and the cap 5 replaced upon the end of the receptacle, the stem 9 protruding through the extension 17 and into the tube 14 to be engaged by the pawl 27 in the manner previously described. A tooth brush may now be inserted upwardly into the housing 1 and into engagement with the clips 22 of the brush engaging member 21. The housing 1 provides a sanitary case for keeping the brush while not in use. The grip afforded by the clips 22 upon the body portion of the brush 24 is sufficient to cause the member 21 to be moved downwardly with the brush against the spring 31 when the brush is withdrawn from the housing 1, until further movement is prevented by closure of the spring against the nut 18 the pawl 27 operating to move the plunger 8 an equal distance. The downward movement of the member 21 causes the slide 29 to move out of engagement with the discharge vent 6 thereby permitting the paste 34 displaced by the downward movement of the plunger 8 to be dispensed through the vent 6. The downward movement of the member 21 in opening the vent 6 brings the lowermost bristles 32 of the brush 24 into contact with the vent 6 to receive the paste therefrom, further movement of the brush causing the paste dispensed to be distributed along the length of the bristle portion of the brush. When further downward movement of the member 21 is prevented by the nut 18 the brush is pulled downwardly out of engagement with the clips 22, the member 21 immediately being returned to its normal position by the spring 31, and a further dispensing of paste through the vent 6 prevented. In this manner the tooth paste is automatically dispensed upon the brush when the brush is withdrawn from the housing thereby avoiding the subsequent inconvenience and delay of opening a container and applying paste therefrom.

55 The clips 22 are positioned to engage the body portion of the brush at approximately its mid point to cause the vent 6 to remain open long enough for the paste displaced by the first downward movement to be dispensed onto the brush.

From the foregoing description it is readily seen that I have provided a convenient and sanitary storage place for both tooth brush and tooth paste in combination with improved means for automatically dispens-

ing paste upon the brush when the brush is withdrawn for use.

Having thus described my invention what I claim as new and desire to secure by Letters Patent is,

1. A tooth paste dispensing device comprising a receptacle; provided with a dispensing vent; brush engaging means mounted adjacent to the receptacle to hold a tooth brush adjacent the dispensing vent; dispensing means mounted within the receptacle; and means operatively connecting the brush engaging means and the dispensing means for operating said dispensing means to dispense tooth paste to the brush when said brush is withdrawn from the brush engaging means.

2. A tooth paste dispensing device comprising a receptacle provided with a dispensing vent; brush engaging means mounted adjacent to the receptacle to hold a tooth brush adjacent the dispensing vent; dispensing means mounted within the receptacle; and means operatively connecting the brush engaging means and the dispensing means for operating said dispensing means to dispense tooth paste to the brush when said brush is withdrawn from the brush engaging means; and means for regulating the quantity of paste dispensed to the brush.

3. A tooth paste dispensing device comprising a receptacle provided with a dispensing vent; brush engaging means mounted adjacent the receptacle to hold a tooth brush adjacent said vent; dispensing means mounted within the receptacle; means operatively connecting the brush engaging means and the dispensing means for operating said dispensing means to dispense tooth paste upon the brush when said brush is withdrawn from the brush engaging means; and means for preventing the dispensing of paste at times other than when the brush is being withdrawn.

4. A tooth paste dispensing device comprising a receptacle provided with a dispensing vent; brush engaging means mounted adjacent the receptacle to hold a tooth brush adjacent said vent; dispensing means mounted within the receptacle; means operatively connecting the brush engaging means and the dispensing means for operating said dispensing means to dispense tooth paste upon the brush when said brush is withdrawn from the brush engaging means; and means for preventing the dispensing of paste at times other than when the brush is being withdrawn; and means for regulating the quantity of paste dispensed to the brush at each operation.

5. A tooth paste dispensing device comprising a housing adapted for mounting upon a wall, said housing being open at one end thereof; a receptacle provided with a dispensing vent removably mounted within

5 said housing; tooth brush engaging means slidably mounted within the housing adjacent the receptacle to hold a tooth brush adjacent the dispensing vent; dispensing means mounted within the receptacle; and means operatively connecting the brush engaging means and the dispensing means for operating said dispensing means to dispense tooth paste upon the brush when said brush is withdrawn from the brush engaging means.

6. A tooth paste dispensing device comprising a housing adapted for mounting upon a wall, said housing being open at one end thereof; a receptacle provided with a dispensing vent removably mounted within said housing; tooth brush engaging means slidably mounted within the housing adjacent the receptacle to hold a tooth brush adjacent the dispensing vent; dispensing means mounted within the receptacle; and means operatively connecting the brush engaging means and the dispensing means for operating said dispensing means to dispense tooth paste upon the brush when said brush is withdrawn from the brush engaging means; and means for regulating the quantity of tooth paste dispensed upon the brush at each operation.

7. A tooth paste dispensing device comprising a housing adapted for mounting upon a wall, said housing being open at one end thereof; a receptacle provided with a dispensing vent removably mounted within said housing; tooth brush engaging means slidably mounted within the housing adjacent the receptacle to hold a tooth brush adjacent the dispensing vent; dispensing means mounted within the receptacle; and means operatively connecting the brush engaging means and the dispensing means for operating said dispensing means to dispense tooth paste upon the brush when said brush is withdrawn from the brush engaging means; and means for regulating the quantity of tooth paste dispensed upon the brush at each operation; and means normally preventing the dispensing of paste except while said brush is being withdrawn.

8. A tooth paste dispensing device comprising a receptacle provided with a dispensing vent; brush engaging means slidably mounted adjacent the receptacle to receive and hold a tooth brush adjacent said vent; a plunger mounted within the receptacle; a stem secured to the plunger and extending outwardly beyond the receptacle; ratchet teeth formed upon said stem; and means operatively connected to the brush engaging means and engaging said ratchet teeth for operating said plunger to dispense tooth paste to the brush when said brush is withdrawn from the brush engaging means.

9. A tooth paste dispensing device comprising a receptacle provided with a dis-

10 pensing vent; brush engaging means slidably mounted adjacent the receptacle to receive and hold a tooth brush adjacent said vent; a plunger mounted within the receptacle; a stem secured to said plunger and extending outwardly beyond the receptacle; ratchet teeth formed upon said stem; and a pawl operatively mounted upon the brush engaging means arranged to engage the ratchet teeth for operating said plunger to dispense tooth paste upon the brush when said brush is withdrawn from the brush engaging means.

10. A tooth paste dispensing device comprising a receptacle provided with a dispensing vent; brush engaging means slidably mounted adjacent the receptacle to receive and hold a tooth brush adjacent said vent; a plunger mounted within the receptacle; a stem secured to said plunger and extending outwardly beyond the receptacle; ratchet teeth formed upon said stem; and a pawl operatively mounted upon the brush engaging means arranged to engage the ratchet teeth for operating said plunger to dispense tooth paste upon the brush when said brush is withdrawn from the brush engaging means; and means for regulating the quantity of paste dispensed to the brush at each operation.

11. A tooth paste dispensing device comprising a receptacle provided with a dispensing vent; brush engaging means slidably mounted adjacent the receptacle to receive and hold a tooth brush adjacent said vent; a plunger mounted within the receptacle; a stem secured to said plunger and extending outwardly beyond the receptacle; ratchet teeth formed upon said stem; and a pawl operatively mounted upon the brush engaging means arranged to engage the ratchet teeth for operating said plunger to dispense tooth paste upon the brush when said brush is withdrawn from the brush engaging means; and means for regulating the quantity of paste dispensed to the brush at each operation; and means for normally preventing the dispensing of tooth paste except while the brush is being withdrawn.

12. A tooth paste dispensing device comprising a housing adapted for mounting upon a wall, said housing being open at one end thereof; a receptacle provided with a dispensing vent removably mounted within said housing; tooth brush engaging means slidably mounted within the housing adjacent the receptacle to receive and hold a tooth brush adjacent said vent; a plunger mounted within the receptacle; a stem secured to the plunger and extending outwardly beyond the receptacle; ratchet teeth formed upon said stem; and a pawl operatively mounted upon the brush engaging means and arranged to engage the ratchet teeth for operating the plunger to dispense

tooth paste to the brush when said brush is withdrawn from the brush engaging means.

13. A tooth paste dispensing device comprising a housing adapted for mounting upon a wall, said housing being open at one end thereof; a receptacle provided with a dispensing vent removably mounted within said housing; tooth brush engaging means slidably mounted within the housing adjacent the receptacle to receive and hold a tooth brush adjacent said vent; a plunger mounted within the receptacle; a stem secured to the plunger and extending outwardly beyond the receptacle; ratchet teeth formed upon said stem; and a pawl operatively mounted upon the brush engaging means and arranged to engage the ratchet teeth for operating the plunger to dispense tooth paste to the brush when said brush is withdrawn from the brush engaging means; and adjustable means for limiting the movement of the brush engaging means when the brush is being withdrawn therefrom to regulate the quantity of paste dispensed upon said brush.

14. A tooth paste dispensing device comprising a housing adapted for mounting upon a wall, said housing being open at one end thereof; a receptacle, provided with a dispensing vent removably mounted within said housing; tooth brush engaging means slidably mounted within the housing adjacent the receptacle to receive and hold a tooth brush adjacent said vent; a plunger mounted within the receptacle; a stem secured to the plunger and extending outwardly beyond the receptacle; ratchet teeth formed upon said stem; and a pawl operatively mounted upon the brush engaging means and arranged to engage the ratchet teeth for operating the plunger to dispense tooth paste to the brush when said brush is withdrawn from the brush engaging means; and adjustable means for limiting the move-

ment of the brush engaging means when the brush is being withdrawn therefrom to regulate the quantity of paste dispensed upon said brush; and means connected to the brush engaging means for normally closing the dispensing vent, and to open said vent when said brush engaging means is operated by the withdrawal of the brush therefrom to dispense paste from the receptacle.

15. A tooth paste dispensing device comprising a housing adapted for mounting upon a wall, said housing being open at one end thereof; a receptacle provided with a dispensing vent removably mounted within said housing; tooth brush engaging means slidably mounted within the housing adjacent the receptacle to receive and hold a tooth brush adjacent said vent; a plunger mounted within the receptacle; a stem secured to the plunger and extending outwardly beyond the receptacle; ratchet teeth formed upon said stem; and a pawl operatively mounted upon the brush engaging means and arranged to engage the ratchet teeth for operating the plunger to dispense tooth paste to the brush when said brush is withdrawn from the brush engaging means; and adjustable means for limiting the movement of the brush engaging means when the brush is being withdrawn therefrom to regulate the quantity of paste dispensed upon said brush; and means connected to the brush engaging means for normally closing the dispensing vent, and to open said vent when said brush engaging means is operated by the withdrawal of the brush therefrom to dispense paste from the receptacle; and means for returning the brush engaging means to its normal position when the brush has been removed therefrom.

In witness whereof I hereunto set my signature.

CHARLES DOYLE.
